Primary Examiner—Catherine Tuttle

(57) **CLAIM**

The ornamental design for the noisemaker, as shown and described.

DESCRIPTION

FIG. 1 is a front elevation view of a noisemaker showing my new design, the left, right and back views being the same as the front;

FIG. 2 is a top view thereof;

FIG. 3 is a bottom view thereof, showing an air valve and stop in broken lines; and,

FIG. 4 is a perspective view thereof.

The broken lines are included for the purpose of illustrating a portion(s) of the noisemaker that form no part of the claimed design.
